UNITED STATES PATENT OFFICE.

JOHN B. SUTCH AND WILLIAM C. McELHENY, OF PITTSBURG, PA.

ROLLER-DIE.

SPECIFICATION forming part of Letters Patent No. 274,840, dated March 27, 1883.

Application filed October 23, 1882. (No model.)

To all whom it may concern:

Be it known that we, JOHN B. SUTCH and WILLIAM C. McELHENY, citizens of the United States of America, residing at Pittsburg, in the county of Allegheny and State of Pennsylvania, have invented certain new and useful Improvements in Roller-Dies, of which the following is a specification, reference being had therein to the accompanying drawings.

Our invention relates to an improvement in roller-dies for rolling and forming steel or iron bars into blanks for nut-locks.

Letters Patent of the United States for an improvement in nut-locks, No. 257,782, bearing date of May 9, 1882, having been granted to John B. Sutch, and finding himself unable to make the said nut-locks by hand with the required rapidity, we have conjointly invented roller-dies to manufacture them, of which the following is a full description, reference being had to the accompanying drawings.

Figure 1 represents a sectional view of the roller; Fig. 2, a side view of the same; and Fig. 3 represents a blank as formed by the roller-die.

The roller A has a groove, *a*, in its circumference, of a depth and width to accord with the thickness and width of the bar to be formed into a blank. At the bottom of the groove are, at regular intervals, depressions *b*, gradually rising to an apex and decreasing in the same manner at the opposite side. These

élévations serve to compress the material to be formed, so as to bevel the under side, the apex or highest part of the elevations reducing the bar at the point *f* to a thinness to be easily cut or broken. Near the center of the distance between two elevations are cavities *c* at the bottom of the groove, one at each side of the central distance, leaving a short space, *d*, between them. The cavities *c* are of the form of an inverted pyramid or cone, so as to produce on the bar, when rolled, at its under side, a pointed projection of that form. The bar, after being rolled and pressed, presents a form as shown in Fig. 3, and has to be cut at *d* and *f*, the resulting pieces being each a blank for one nut-lock of the kind described in said Letters Patent, which pieces have to be bent to be finished.

Having thus described our invention, we claim—

A roller-die provided with the groove *a*, the points *f*, to nearly sever the blank, and the recesses *c*, to form the projections or points on the blank, substantially as shown.

In testimony whereof we affix our signatures in presence of two witnesses.

JOHN B. SUTCH.
WILLIAM C. McELHENY.
